See application file for complete search history.

The ornamental design for an umbrella, as shown and described.

(56) **References Cited****DESCRIPTION**

U.S. PATENT DOCUMENTS

FIG. 1 is a perspective view of an umbrella showing a new design;

878,270 A	2/1908	Blake et al.
956,657 A	5/1910	Wetteroth
957,528 A	5/1910	Wetteroth
D45,227 S	2/1914	Glauber
1,136,887 A	4/1915	Penn
1,235,296 A	7/1917	Dillingham
1,243,594 A	10/1917	Dillingham
1,255,627 A	2/1918	Morrow et al.
1,268,354 A	6/1918	Howard
1,801,913 A	4/1931	Frederick
D90,772 S	9/1933	Kasch
D127,735 S	6/1941	Dreyfuss
2,447,972 A	8/1948	Weinert
2,475,406 A	7/1949	Russell

FIG. 2 is a detail view of the new umbrella design of FIG. 1 taken at 2 shown in FIG. 1;

FIG. 3 is a front or rear view of the design of FIG. 1;

FIG. 4 is a detail view of the new umbrella design of FIG. 1 taken at 4 shown in FIG. 3;

FIG. 5 is a right or left side view of the design of FIG. 1;

FIG. 6 is a detail view of the new umbrella design of FIG. 1 taken at 6 shown in FIG. 5;

FIG. 7 is a top view of the design of FIG. 1;

FIG. 8 is a detail view of the new umbrella design of FIG. 1 taken at 8 shown in FIG. 7;

FIG. 9 is a bottom view of the design of FIG. 1; and,

FIG. 10 is a detail view of the new umbrella design of FIG. 1 taken at 10 shown in FIG. 9.

The broken lines depict portions of the article that form no part of the claimed design.
